CLAIM

The ornamental design for a watertight accessory container, as shown and described.

DESCRIPTION

FIG. 1 is a right side perspective view of a watertight accessory container, showing my new design;

FIG. 2 is a left side perspective view; and

FIG. 3 is a left side elevational view, the opposite side being a mirror image thereof.

The side opposite that shown in FIG. 3 is identical thereto.

The design is characterized by the specifically configured retaining clip in combination with the particular bifurcated tube, all as best illustrated in FIGS. 1 and 2.
